PREFILL VALVE FOR HYDRAULIC PRESSES

Earl Cannon, Rockville Centre, N. Y., assignor
to E. W. Bliss Company, Brooklyn, N. Y., a cor-
poration of Delaware

Application October 10, 1936, Serial No. 105,005

19 Claims. (Cl. 121—38)

This invention relates to improvements in prefill valves for permitting the rapid filling of the ram work chamber of a hydraulic press with oil or other fluid prior to setting up high pressure therein, and is described and illustrated herein as applied to such valves wherein means are provided for quickly advancing the press ram into engagement with the work.

Heretofore the quick advance of the main ram in some hydraulic presses has been accomplished by the use of one or more auxiliary rams, operated under relatively low pressure. During the advance of the main ram in such presses, and as a result of suction created thereby, fluid from a nearby reservoir is drawn through the prefill valve into the ram work chamber of the press, whereupon the prefill valve is closed to permit the setting up of pressure in said chamber sufficient to perform the desired work. For compactness and direct connection, both the prefill valve and a fluid tank have in many presses been mounted on the top of the press, co-axially with the ram chamber, the quick advance of the ram being accomplished by means independent of said ram. In other presses a rod or conduit extends axially within the ram to conduct fluid into a quick-advance chamber therein, and the prefill valve is mounted toward one side of the axis of the ram and is connected to the tank and the ram chamber by suitable pipe connections. My present invention embodies a combination of these two arrangements, resulting in a more compact and highly efficient structure which may be economically constructed and maintained.

My invention is disclosed and described herein as applied to a spring-opening type of valve which has certain advantages over a spring-closing type of valve. The latter type, if arranged to depend upon the suction in the ram work chamber to cause it to open, and permit the flow of liquid into said chamber as the ram advances, opens only to a very limited degree and, therefore, does not permit a free and rapid flow of liquid into the said chamber. Such spring-closing type valves, of course, may be and have been provided with auxiliary hydraulic chambers to cause them to open by hydraulic pressure, in which case additional pipes and auxiliary valves are necessary to control the movement of the prefill valve. It is obviously desirable, both from the standpoint of efficiency of operation and compactness of design, to minimize the piping employed in such presses.

An important object of my invention is the provision of a spring-opening type of prefill

valve which will not have the objectionable characteristics of the spring-closing type of valve as aforesaid and may be arranged to directly co-act with the means for effecting quick advance of the ram and to directly connect with a tank to permit rapid filling of the ram work chamber as the ram advances.

A further object of the invention is the provision of a compact arrangement of prefill valve, a tank, and a rod or conduit for conducting fluid into a quick-advance chamber in the ram, all co-axially disposed relatively to the ram of a press, such arrangement requiring a minimum of piping and yielding a maximum of efficiency.

A further object of the invention is the provision of means within the valve structure for bypassing pressure from a point at one side of the valve to the ram work chamber at the other side thereof, after the valve has been closed, thus additionally minimizing the piping that is necessary for operating a press.

The foregoing and other objects are accomplished by my invention as described and defined in the following specification and claims and as illustrated in the accompanying drawings, in which:

Figure 1 is a vertical cross-section of a valve according to my invention.

Fig. 2 is a vertical cross-section of a modified form of valve.

Fig. 3 is a horizontal section, looking upward, on the line 3—3 of Fig. 2.

Fig. 4 is a vertical cross-section of a still further modification of my invention.

Fig. 5 is a horizontal section, looking upward, on the line 5—5 of Fig. 4.

Fig. 6 is a vertical cross-section of another modification of my invention.

In the embodiment of my invention illustrated in Fig. 1, I employ a substantially cylindrical casing 11 having coaxial bores 12 and 13 toward the upper and lower ends, respectively, of said casing. A removable head 14 is secured upon the upper end of the casing 11 by bolts 15 (only one of the latter appearing in the drawings).

A co-axial passage 16, of lesser diameter than the bore 12, extends between the latter and the bore 13 to permit the passage of fluid therebetween. The wall of this passage is formed by an annular valve seat 17, fitted tightly within the casing 11, and having a vertical seating surface 18 and an oblique seating surface 19.

A slideable valve element 20 is accurately fitted within the bore 12 and is adapted to reciprocate therewith between an open position,—as indi-

5

55

cated in the drawings, wherein the upward movement of said element is limited by the head 14,—and a closed position, wherein the downward movement of the valve element is limited by the valve seat 17; said valve element having a vertical seating surface 21 and an oblique seating surface 22, which seating surfaces, respectively, cooperate with the seating surfaces 18 and 19 of the valve seat 17.

10 A compression spring 23 is disposed about a reduced lower portion of the valve element 20, and seats against the valve seat 17 and a shoulder 24 on the valve element 20 to hold the latter in an open position. A tank 25 is suitably mounted 15 upon the casing 11 and substantially surrounds the valve structure. One or more openings 26 are provided in the casing 11 leading into a surge chamber 27 in the lower part of the bore 12 for permitting a free flow or surge of fluid between the tank 25 and said chamber at substantially atmospheric pressure.

18 The bore 12 serves as a valve chamber comprising the surge chamber 27 and a valve-closing chamber 28 of inversely variable volumes, 25 which vary with the reciprocation of the valve element 20 therewithin. A port 29 opens into the valve-closing chamber 28 to permit the admission of fluid thereto under pressure to move the valve element to its closed position.

20 The bore 13 serves as a ram chamber comprising a ram work chamber 30 and a ram return chamber 30^a of inversely variable volumes, within which chambers a reciprocating ram 31 is accurately fitted. This ram is somewhat elongated and substantially cylindrical in shape. An upper portion of the ram is of enlarged diameter and works within the said chambers between a raised position, as indicated in full lines in the drawing, and a lowered or advanced position, as 35 indicated in broken lines. The remainder of the ram is of reduced diameter and extends downwardly beyond the casing 11 to engage the material being worked upon by the press, a ring 32 being fixed within the lower end of said casing 40 and about the ram to prevent leakage of fluid from the ram return chamber 30^a.

45 The interior of the ram 31 is hollowed to form a cylindrical quick-advance chamber 33 therewithin. An elongated rod 34 is fixed to the head 50 14 by a nut 35 and extends downwardly centrally through the valve-closing chamber 28, the surge chamber 27, the passage 46, and the ram work chamber 30. The said rod extends through a bore 36 in the valve element 20 and a bore 37 in the 55 upper portion of the ram 31, and terminates within the quick-advance chamber 33. The rod 34 has an axial passage 38 extending throughout its length and opening into the quick-advance chamber 33 to permit the admission of fluid 60 thereto under sufficient pressure to quickly advance the ram 31 into engagement with the material being worked.

65 A port 30^b is provided to permit the exhaustion of fluid from the ram return chamber 30^a on the advance stroke of the ram and to admit fluid into said chamber to return the ram to a raised position.

70 It will be seen that after the ram has been lowered or advanced into engagement with the material being worked, by the admission of fluid into the quick-advance chamber 33, and the valve element 20 has been moved to a closed position, the ram work chamber 30 will contain fluid at substantially atmospheric pressure, and the fluid 75 pressure in said chamber must be increased to

impose sufficient pressure upon the ram to enable it to perform the desired work. A source of fluid pressure could, of course, be independently connected to said chamber, necessitating a separate pipe connection for that purpose. According to 5 my invention, however, the use of such separate connections may be avoided, and to this end I employ a by-pass arrangement whereby the port 29, which admits fluid into the valve-closing chamber 28, also serves for establishing suitable 10 fluid pressure in the ram work chamber 30.

A bore 39 is provided extending within the wall of the casing 11 from a point opposite the valve-closing chamber 28 to a point near the ram work chamber 30, an opening 40 connecting said bore 15 with said valve-closing chamber and a passage 41 connecting said bore with the ram work chamber. A check valve 42 is arranged to be held closed across the opening 40 by a compression spring 43 co-acting with a screw plug 44 which 20 also serves as a guide for said check valve. The compression of the spring 43 is such that the check valve 42 may not open until the pressure within the valve-closing chamber 28 exceeds the pressure required to move the valve element 20 25 to a closed position.

The cycle of operation commences with the various parts in the positions shown in full lines in the drawings and with fluid under substantially atmospheric pressure in the tank 25 and in 30 all the various chambers and passages referred to, except in the ram return chamber 30^a wherein sufficient pressure is present to hold the ram 31 in a raised position.

35 Fluid is admitted under moderate pressure into the quick-advance cylinder 33 through the passage 38 in the rod 34, the ram return cylinder 30^a, meanwhile, being permitted to exhaust through the port 30^b. This causes the ram 31 to descend into engagement with the material being 40 worked. The descent of the ram causes fluid from the tank 25 to be drawn or sucked through the openings 26 into the surge chamber 27 and thence through the passage 46 into the ram work chamber 30. 45

Fluid is then admitted under relatively high pressure through the port 29 into the valve-closing chamber 28, causing the valve element 20 to descend to a closed position. The continued introduction of pressure through the port 29 sets 50 up pressure in the valve-closing chamber 28 sufficient to open the check valve 42 and establish communication between the valve-closing chamber 28 and the ram work chamber 30 through the opening 40, the bore 39, and the passage 41, and 55 thus introduces a suitable working pressure into the ram work chamber 30. The pressure introduced into the said ram work chamber through the port 29 may be raised to the extent necessary to permit the ram to fully perform its desired 60 work. At this stage of the cycle the ram 31 is in substantially the position indicated in broken lines in the drawings.

It will be seen that after the check valve 42 65 opens, a substantially uniform fluid pressure is present in both the valve-closing chamber 28 and the ram work chamber 30. As the upper surface of the valve element 20, which is subjected to downward pressure, is of greater area than the lower surface thereof, which is subjected to upward pressure, it is obvious that there is a predominant downward force exerted upon the valve element 20 which operates to hold said element in a closed position while working pressure is maintained in the ram work chamber, it being 70 75

apparent that the excess downward force must be sufficient to overcome in addition the expansive force of the spring 23.

The return stroke of the ram is accomplished by simultaneously releasing the pressure in the valve-closing chamber 28 and the quick-advance chamber 33 and introducing fluid under pressure into the ram return chamber 30a, thereby permitting the exhaustion of the chambers 28 and 33, allowing the spring 23 to raise the valve element 20, and forcing the ram 31 upwardly to its uppermost position and permitting the fluid in the ram work chamber 30 to surge upwardly and outwardly through the passage 18, the surge chamber 27, and the openings 26 into the tank 25, thereby completing the cycle.

It is highly desirable to provide means whereby, on the return stroke of the ram 31, as aforesaid, the pressure within the ram work cylinder 30 may be gradually relieved and reduced to substantially atmospheric pressure, as otherwise the instantaneous release of such pressure upon the unseating of the valve element 20, combined with the action of the spring 23, gives rise to severe shock and to detrimental structural stresses in the press. Means to this end are disclosed and claimed in my co-pending application, Serial No. 111,790, filed Nov. 20, 1936. As disclosed herein, these means comprise a plurality of vertical grooves 45 of various lengths in the lower part of the valve element 20. These grooves are disposed about and interrupt the vertical seating surface 21 of the said valve element and extend to the lower edge of said surface. As the valve element 20 rises on the return stroke of the press, the longer grooves 45 and then the shorter grooves 45, in succession, extend beyond the upper edge of the vertical seating surface 18 of the valve seat 17,—thus establishing a relatively gradual fluid connection between the tank 25 and the ram work chamber 30 and permitting a relatively gradual reduction of the pressure within the latter, thereby eliminating any objectionable shock and structural stresses. This operation, although taking place progressively to release the pressure, takes place as a practical proposition in a fraction of a second.

The embodiments of Figs. 2 and 4 differ from that of Fig. 1 in having a valve casing 46 and a separate ram casing 47. They differ also from the embodiment of Fig. 1 in the means for bypassing fluid pressure from the valve-closing chamber 28 to the ram work cylinder 30 to establish a relatively high working pressure in the latter.

The by-passing means illustrated in Fig. 2 comprise grooves or slots 48 in the axial bore in the valve element 20 extending throughout the entire length of said bore. While these grooves are sufficiently large to by-pass fluid under pressure, they, nevertheless, are sufficiently small to frictionally retard the passage of fluid therethrough and to permit the accumulation of pressure in the valve-closing chamber 28 to cause the valve element 20 to move downwardly to a closed position as a result of the introduction of fluid into said chamber through the port 29. Once the valve element 20 reaches its closed position, the greater total force upon the upper surface thereof, as compared to the total force upon the lower surface thereof, operates to hold the said valve element in a closed position against the compression of the spring 23.

It is obvious that larger or greater numbers of by-pass grooves 48 may be provided, the design

of the valve in this respect being governed in a measure by the viscosity of the fluid to be used. In any event, such grooves must not be large enough in the aggregate to pass fluid with sufficient rapidity to prevent the accumulation of pressure in the chamber 28 upon the initial introduction of fluid into said chamber through the inlet 29, as under such conditions the valve would be prevented from closing.

The by-passing means illustrated in Fig. 4 comprise an annular passage 49 formed by the enlargement of the lower portion of the bore 36 in the valve element 20 and extending from the bottom to a point near the top of said valve element. Fluid connection is provided between the passage 49 and the valve-closing chamber 28 by an eccentrically-disposed axial passage 50 in the valve element 20 extending from the top thereof to a point therein opposite the upper end of the annular passage 49, and by an opening 51 connecting the latter with the passage 49. A check valve 52 is guided within a bore 53 at the lower end of the said axial passage and urged by a compression spring 54 within the bore 53 toward a closing position across the lower end 25 of a tubular threaded seat 55 which is screwed into the upper end of the axial passage 50.

The by-passing means illustrated in Figs. 1 and 4 operate similarly, but differ principally in that in the former the by-pass check valve and passages are in the valve casing, while in the latter they are in the slide valve. Although the accompanying drawings show only one by-pass check valve in each embodiment, it is obvious that two or more such valves may be utilized, if desired.

Fig. 6 illustrates by-passing means which are very similar to and function similarly to the by-passing means shown in Fig. 1, the principal differences being that the by-pass fluid connection between the valve-closing chamber 28 and the ram work chamber 30 comprises pipe connections 39a disposed outside of the valve structure, instead of the bore 36, opening 40, and passage 41 shown in Fig. 1 in the valve casing, and that a check valve 56 of modified form is employed for the same purpose as the check valve disclosed in Fig. 1.

Suitable pumping and valving means (not shown) are provided in the several modifications to time and otherwise control the admission of fluid into the several chambers and the exhaustion thereof to achieve the desired cycle of operation and the necessary fluid pressures.

My invention has been described herein and illustrated in the accompanying drawings, solely for illustrative purposes, as employed in a vertical press with a descending ram, but it may obviously be employed in a horizontal press or in a vertical press with an ascending ram or in presses disposed at any angle. Its employment in such various presses and in various modifications may obviously be resorted to without departing from the spirit of the invention.

What I claim is:

1. The combination with a hydraulic press having a ram chamber, a ram adapted to reciprocate within said chamber, and a fixed rod extending within a bore in the ram, of a prefill valve comprising a casing within which the said fixed rod extends, a surge chamber in said casing communicating with the ram chamber, an opening in said casing arranged to permit the flow of fluid into said surge chamber, a valve element slidably mounted upon said fixed rod within said

casing, and means for reciprocating said valve element within said surge chamber to control the flow of fluid between the latter and the ram chamber, the fixed rod being fixedly connected 5 to said casing.

2. The combination according to claim 1 wherein the said ram, fixed rod, and valve element all have a common axis of symmetry.

3. The combination according to claim 1 10 further characterized in having a tank for holding fluid, said prefill valve being disposed substantially within said tank in a position to be immersed in fluid therein whereby to permit the ready flow thereof between said valve and said 15 tank.

4. The combination according to claim 1 further characterized in having an interior hydraulic chamber in the ram and the said fixed rod having an axial passage opening into said 20 interior hydraulic chamber and being adapted to conduct fluid thereinto to advance the ram.

5. The combination with a hydraulic press having a ram chamber, a ram adapted to reciprocate within said chamber, and a fixed rod extending 25 within a bore in the ram, of a prefill valve comprising a casing, an annular valve chamber, within which the said fixed rod extends, having an opening in the wall thereof to permit the passage of fluid thereinto, an annular communicating passage between said valve chamber and the ram chamber, an annular valve element within said valve chamber extending around and adapted to slide upon said rod, and means for 30 sliding the valve element between an open position and a closed position wherein a portion of said element extends across and closes said passage, the fixed rod being fixedly connected to 35 said casing.

6. The combination in a hydraulic press of 40 a ram chamber, a valve-closing chamber, a surge chamber, and a communicating passage between the latter and the ram chamber, all having a common axis of symmetry, a reciprocating ram adapted to hydraulically work within the ram chamber, a reciprocating slide valve element adapted to hydraulically work within the valve-closing chamber and the surge chamber and having a seating portion adapted to seat across 45 and close said passage when in a closed position, a fixed rod extending centrally through the said valve element and communicating passage and into the reciprocating ram, an opening in the wall of said surge chamber to permit the admission of fluid thereinto, and spring means for urging 50 the said valve element toward an open position wherein fluid may flow freely through said passage, the valve-closing chamber being adapted to receive fluid thereinto under pressure to urge the valve element toward a closed position against the force of said spring means, the said press 55 having a casing to which the fixed rod is fixedly connected.

7. The combination, in a hydraulic press, of 60 a ram chamber, a reciprocating valve element adapted when in a closed position to substantially close the said ram chamber whereby to permit establishment of working pressure therein, a valve-closing chamber adapted to hydraulically move said valve element to its closed position, and means for passing fluid from the latter 65 chamber to the ram chamber to establish working pressure therein, said means comprising a continuously open passage connecting the two said chambers, the said passage being of such 70 restricted area that, as fluid passes therethrough 75

toward the ram chamber, sufficient back pressure is created in the valve-closing chamber to move the said valve element to its closed position.

8. The combination according to claim 7, further characterized in that the said passage is in 5 the said valve element and affords fluid connection between the two said chambers when the said element is in closed position.

9. The combination, in a hydraulic press, of 10 a ram chamber, a surge chamber normally in open communication therewith, a casing, a valve-closing chamber, a reciprocating ram movable within the ram chamber, a reciprocating valve element movable within the valve-closing chamber and the surge chamber and having an inner 15 end adapted to substantially close the surge chamber and ram chamber against communication when said valve element is in a closed position and having an outer end adapted to receive hydraulic pressure to urge the valve element to 20 a closed position, and means for transmitting fluid pressure between the valve-closing chamber and the ram chamber, a rod being provided which is fixed to said casing and extends through the said said valve element and into said reciprocating 25 ram.

10. The combination according to claim 9, the said means for transmitting fluid pressure comprising an interior longitudinal groove in the valve element adjacent to the fixed rod and forming, with the latter, a passage for transmitting 30 fluid pressure between the valve-closing chamber and the ram chamber.

11. The combination according to claim 9, the said means for transmitting fluid pressure comprising an annular passage extending around the fixed rod at one end of the valve element and a duct extending from said passage to the other end 35 of the valve element.

12. The combination, in a hydraulic press, of 40 a ram chamber, a surge chamber normally in open communication therewith, a casing, a valve-closing chamber, a reciprocating ram movable within the ram chamber, a reciprocating valve element movable within the valve-closing chamber 45 and the surge chamber and having an inner end adapted to substantially close the surge chamber and ram chamber against communication when said valve element is in a closed position and having an outer end adapted to receive hydraulic 50 pressure to urge the valve element to a closed position, and means for transmitting fluid pressure between the valve-closing chamber and the ram chamber, the said casing substantially surrounding all said chambers, and the said means 55 comprising a passage in said casing adapted to transmit fluid pressure between the valve-closing chamber and the ram chamber.

13. The combination according to claim 12, further characterized in having a valve adapted 60 to permit transmission of pressure between the valve-closing chamber and the ram chamber only when the pressure in the valve-closing chamber is greater than required to move the valve element to a closed position.

14. The combination, in a hydraulic press, of a ram chamber, a surge chamber normally in open communication therewith, a casing, a valve-closing chamber, a reciprocating ram movable within the ram chamber, a reciprocating valve element 70 movable within the valve-closing chamber and the surge chamber and having an inner end adapted to substantially close the surge chamber and ram chamber against communication when said valve element is in a closed position and hav- 75

ing an outer end adapted to receive hydraulic pressure to urge the valve element to a closed position, and means for transmitting fluid pressure between the valve-closing chamber and the 5 ram chamber, the said means comprising pipe passages connecting the valve-closing chamber and the ram chamber.

15. The combination according to claim 14, further characterized in having a valve adapted 10 to permit transmission of pressure between the valve-closing chamber and the ram chamber only when the pressure in the valve-closing chamber is greater than required to move the valve element to a closed position.

15. 16. The combination according to claim 9, the said means for transmitting fluid pressure comprising an interior longitudinal passage in the valve element adjacent to and partly defined by the fixed rod, the said passage being of such restricted area that, as fluid from the valve-closing chamber passes therethrough, sufficient back pressure is created in the valve-closing chamber to close the valve and permit the establishment of working pressure in the ram chamber.

25. 17. The combination according to claim 9, further including spring means coacting with the reciprocating valve element whereby to urge the latter toward an open position, the said means

for transmitting fluid pressure comprising an interior longitudinal passage in the valve element adjacent to and partly defined by the fixed rod, said passage being of such restricted area that, as fluid from the valve-closing chamber passes therethrough, sufficient back pressure is created in the valve-closing chamber to close the valve element against the action of said spring means. 5

18. The combination according to claim 7, further including spring means coacting with the reciprocating valve element whereby to urge the latter toward an open position, the back pressure created in the valve-closing chamber being sufficient to move the said valve element to its closed position against the action of said spring means. 10 15

19. The combination according to claim 7, further including spring means coacting with the reciprocating valve element whereby to urge the latter toward an open position, the back pressure created in the valve-closing chamber being sufficient to move the said valve element to its closed position against the action of said spring means, 20 the said passage being in the said valve element and affording fluid connection between the two said chambers when the said element is in closed position. 25

EARL CANNON.
